UNITED STATES PATENT OFFICE.

FRANK W. BEBERDICK, OF WEST HOBOKEN, NEW JERSEY.

DESIGN FOR A COAT-PATTERN.

SPECIFICATION forming part of Design No. 30,214, dated February 14, 1899.

Application filed November 8, 1898. Serial No. 695,899. Term of patent 14 years.

To all whom it may concern:

Be it known that I, FRANK W. BEBERDICK, a citizen of the United States, residing at West Hoboken, in the county of Hudson and State of New Jersey, have invented and produced a new and original Design for a Coat-Pattern, of which the following is a specification, reference being had to the accompanying drawing, forming part thereof.

10 The drawing represents in plan view a pattern of one side and half of the back of the coat, showing my new design, and it will be understood that the other side and half of the back are the same.

15 As shown in the drawing, the leading or material feature of my design consists in the part A, forming one side and half the front, and the part B, forming half of the back, and in the particular shape or contour given 20 to the upper edge or ends of these parts. From the point a the edge of the part A is curved outwardly and then inwardly and upwardly to the point a^2 , forming the compound-curved line a^1 . From the point a^2 the edge 25 extends upwardly in substantially a straight line, which is slightly curved inwardly at the upper extremity a^3 . From the point a^3 the edge curves inwardly and then upwardly to the point a^5 , forming the curved line a^4 , which 30 constitutes a part of the neck-opening. From the point a^5 the compound-curved line a^6 extends to the point a^7 , which point is located below the point a^5 , but is substantially on the same horizontal plane as point a^3 . The compound-curved line a^6 represents the shoulder 35 line or seam. The edge of the upper portion of the part A extends downwardly and inwardly from the point a^7 in a curve deviating only slightly from a straight line to the point C^2 , from which point the said edge is curved 40 in a small semicircle to the point C^3 . From the point C^3 the edge extends downwardly in a curve deviating only slightly from a straight line to the point a^8 , which is located vertically 45 beneath the point C^3 . From the point a^8 the edge extends substantially horizontally in a compound-curved line which deviates only slightly from a straight line to the point a , at which point the edge is curved upwardly.

50 The outer edge of the lower portion of the part A (designated for convenience by the letter D) extends downwardly from the point d

in substantially a straight line d' , which is inclined sharply inwardly from the perpendicular. From the point d' the edge curves downwardly to the point d^2 , from which point the edge extends in a straight line slightly inclined upwardly to the point d^3 . From the point d^3 the edge extends to the point d^4 . From the point d^4 the edge extends upwardly and inwardly in a curved line to the point d^5 , and thence at a sharp angle to the point d^6 , which point is on substantially the same horizontal plane as the point d . From the point d^6 the edge extends in a straight line slightly 65 upwardly inclined to the point d^7 , from which point the edge extends in a curved line deviating only slightly from a straight line to the point d .

The part C of the design is curved on its 70 upper edge from the point e' to the point e^2 to conform with the curved line from C^2 to C^3 . From the point e' the edge of the part C extends downwardly in a curved line to the point e , which point is located near the point 75 a^8 and slightly above the upper edge of the part D. The adjacent edges of the parts A and C being reversely curved are separated by the space S. From the point e the edge of C extends to the point e^5 in a curve deviating 80 only slightly from a straight line. From the point e^5 the edge of C extends in a straight line slightly inclined downwardly to the point e^4 , which portion of the said edge coincides 85 with the edge d^7 d^6 of the part D. The different curvatures of the adjacent edges of the parts C and D form the space S', and the different curvatures of the adjacent edges of the parts A and D form the irregular spaces S^2 and S^3 . From the point e^4 the edge of the part 90 C extends upwardly in a compound-curved line to the point e^3 , which point is located in substantially the same vertical plane as the point e^4 . From the point e^3 the edge of the part C extends in an upwardly-curved line 95 to the point e^2 , which point is located in substantially the same vertical plane as the point e .

The outer edge of the part B extends in a straight line from its extreme upper point b^3 to the point b^4 and from thence at substantially right angles to the point b^5 . From the point b^5 the edge extends in a straight line to the point b^6 and from thence inwardly

at substantially right angles to the point b^9 . From the point b^9 the edge of the part B extends vertically upward in a straight line to the point b^{11} and from thence at substantially 5 right angles to the point b^{10} . From the point b^{10} the edge of the part B extends upwardly in a vertical straight line and then curves inwardly to the point b . The adjacent edges of the parts B and C are in contact from the 10 point b to the point e^3 , from which last-named point the said edges diverge, thus forming the space S^4 . From the point b the edge of the part B extends upwardly, curving inwardly to the point b' , which is opposite but 15 slightly below the point a^7 of the part A and separated therefrom by the narrow space b^{12} . From the point b' the edge of the part B extends upwardly in a straight but sharply-inclined line to the point b^2 , thus giving the

shape of an obtuse angle to the point b' . The 20 upper edge of the part B extends from the point b^2 in a downward curve to the point b^3 , which point is located slightly below the point b^2 , but on substantially the same horizontal plane as the point a^5 of the part A. 25

Having fully described my invention, I claim as new and desire to secure by Letters Patent—

The design for a coat-pattern as herein shown and described. 30

In testimony that I claim the foregoing as my invention I have signed my name, in presence of the subscribing witnesses, this 29th day of October, 1898.

FRANK W. BEBERDICK.
